The ornamental design for an automobile rearview mirror, as shown and described.

DESCRIPTION

FIG. 1 is a front, top, right side perspective view of automobile rearview mirror, showing our new design; FIG. 2 is a rear, top, left side perspective view thereof; FIG. 3 is a rear, top, right side perspective view thereof; FIG. 4 is a front elevational view thereof; FIG. 5 is a rear elevational view thereof; FIG. 6 is a left side elevational view thereof; FIG. 7 is a right side elevational view thereof; FIG. 8 is a top plan view thereof; and, FIG. 9 is a bottom plan view thereof.

The broken lines illustrate portions of the automobile rearview mirror that form no part of the claimed design.
